TOURNIQUET

Norman W. Brothers, Providence, R. I.

Application July 12, 1943, Serial No. 494,358

2 Claims. (Cl. 128—327)

My invention relates to first aid appliances, and has among its objects and advantages the provision of an improved tourniquet so designed as to require little time in its application, and in which the construction is further designed to eliminate cuts, burns and bruises incident to ties which are drawn tightly about the limb.

In the accompanying drawing:

Figure 1 is a view illustrating an application of the invention to the arm.

Figure 2 is a perspective view of a twisting handle.

Figure 3 is a perspective view of the limb encircling part of the tourniquet, and

Figure 4 is a sectional view taken along the line 4—4 of Figure 3.

In the embodiment of the invention selected for illustration, I make use of a leather strap 10 of such length as to have overlapping relationship at its ends, as at 12 in Figure 1. The strap ends are tapered to feather edges 14 so that the limb engaging face 16 of the strap 10 will fit uniformly tight about the limb. A draw cord 18 circumferentially embraces the outer face of the strap 10 and is held thereon by guides 20.

Each guide 20 comprises a bar 22 spaced from the strap 10 by spacing sleeves 24 mounted on rivets 26 which fixedly secure the bar to the strap.

The ends of the cord 18 are connected with a twisting handle 28. This handle is provided with at least two slots 30 extending inwardly from its vertical edges 32. One end of the cord 18 is knotted at 34 and the cord length adjacent the knot is pressed into one of the slots 30. The other end is wrapped two or three times about the other end of the handle 28 and in the two slots 30 at that end. After such connection of the cord 18, the handle 28 is turned to place a twist 36 in the

cord 18, to draw the strap 10 tightly about the limb 38.

The cord 18 is easily connected with the handle 28, and the handle provides a means whereby the cord may be effectively twisted to constrict the strap 10 upon the limb. The strap provides an effective constricting element and lies between the limb and the cord 18 so as to protect the limb from damage which would occur in case the cord 10 alone were directly applied to the limb. The strap 10 is preferably formed of relatively thick leather and of such stiffness as to eliminate free bending. Thus the strap ends will slide freely relatively to one another as the cord 18 is progressively twisted.

Without further elaboration, the foregoing will so fully explain my invention, that others may, by applying current knowledge, readily adapt the same for use under various conditions of service.

I claim:

1. A tourniquet comprising a flexible strap adapted to be bent about a limb and having tapered overlapping ends, a plurality of guides attached to the exterior face of the strap, each of said guides having a bar disposed transversely of the strap, a rivet connecting each end portion of the bar with the strap, a spacing sleeve on each rivet interposed between the bar and the strap, and a cord extending circumferentially of said strap and through the respective guides thereon.

2. A tourniquet as claimed in claim 1 comprising a handle for twisting the cord to constrict the strap upon a limb, said handle having spaced notches adapted to receive a knotted end of the cord in one of said notches and to have the other end of the cord wrapped about other notches therein.

NORMAN W. BROTHERS.
